Primary Examiner — Michael A Pratt(74) *Attorney, Agent, or Firm* — Vidas, Arrett & Steinkraus**CLAIM**

The ornamental design for an archery bow riser, as shown and described.

DESCRIPTION

FIG. 1 is a perspective view of the archery bow riser.

FIG. 2 is a first side view of the archery bow riser.

FIG. 3 is a second side view of the archery bow riser.

FIG. 4 is a front view of the archery bow riser.

FIG. 5 is a back view of the archery bow riser.

FIG. 6 is a top plan view of the archery bow riser; and,

FIG. 7 is a bottom view of the archery bow riser.

The broken lines near the handle/grip area in FIGS. 1-3 form the boundary of the claim, with the broken lines themselves forming no part of the claimed design. The broken lines showing the limbs, rotatable members, cables and cable positioning device are included for the purpose of illustrating environment and do not form a part of the claimed design.
